CLAIM

The ornamental design for a neuro sub-temporal plate for osteosynthesis, as shown and described.

DESCRIPTION

FIG. 1 is a perspective view of a first embodiment of a neuro sub-temporal plate for osteosynthesis showing my new design;

FIG. 2 is a top view of the neuro sub-temporal plate for osteosynthesis of FIG. 1;

FIG. 3 is a bottom view of the neuro sub-temporal plate for osteosynthesis of FIG. 1;

FIG. 4 is a front view of the neuro sub-temporal plate for osteosynthesis of FIG. 1, with the understanding that the back view is a mirror image of the front view;

FIG. 5 is a right side view of the neuro sub-temporal plate for osteosynthesis of FIG. 1, with the understanding that the left side view is a mirror image of the right side view;

FIG. 6 is a perspective view of a second embodiment of a neuro sub-temporal plate for osteosynthesis;

FIG. 7 is a top view of the neuro sub-temporal plate for osteosynthesis of FIG. 6;

FIG. 8 is a bottom view of the neuro sub-temporal plate for osteosynthesis of FIG. 6;

FIG. 9 is a front view of the neuro sub-temporal plate for osteosynthesis of FIG. 6, with the understanding that the back view is a mirror image of the front view; and,

FIG. 10 is a right side view of the neuro sub-temporal plate for osteosynthesis of FIG. 6, with the understanding that the left side view is a mirror image of the right side view.
